UNITED STATES PATENT OFFICE

2,431,346

LAYOUT TOOL

Thomas F. Scanlin, Philadelphia, Pa.

Application August 11, 1945, Serial No. 610,383

2 Claims. (Cl. 33—27)

(Granted under the act of March 3, 1883, as
amended April 30, 1928; 370 O. G. 757)

1

This invention relates to layout instruments for marking the proper cuts to be made in a ship or other structure in which shaft tubes or other cylinders are to be installed.

More particularly this invention is directed to a longitudinal member, such as a small pipe, mounted on a series of supports in a manner so that the center line of the pipe corresponds to the center line of the larger tube or cylinder to be installed. An adjustable scribe attached to the pipe as by a slip fitting T may be moved along the pipe and revolved about it. It will mark the desired straight or curved lines and arcs of circles on all intersecting surfaces on which a cut is to be made. The scribe, depending on the use to which it is to be put, will be straight or hooked at its end. It is adjustable and so can be made to equal the radius of the cylinder for which the markings are being made. A screw threaded sleeve may receive the hooked scribe end or it may be made in one piece.

The supports preferably comprise a number of perforated target plates slotted for ingress and egress of an aligning center line wire. The target plates are tack welded to braces after which the centerline wire is removed and the small pipe inserted through the aligned perforations.

Prior to these improvements, the practice was to cut the ship's or other structure to a greater extent than required and then to use collars to close the cut after installation of the cylinder. This practice requires considerable judgement and is expensive and wasteful in time and labor and where clearances are small is highly unsatisfactory.

As will be apparent from the description and drawing, the hooked scribe will be used for marking closed curves such as are formed by a cylinder when its center line intersects the deck at an angle greater than 45° and for marking arcs on surfaces which form an angle greater than 45° with the center line of the cylinder. The straight scribe will be used principally for straight lines and curves generated by cylinders whose center lines intersect the deck at angles less than 45° .

The small pipe mentioned above will constitute a longitudinal pivot means so supported that its centerline will correspond with the centerline of the cylinder after installation. It will be understood that the term centerline as used in the claims includes the extension of the actual centerline of the installation.

It will be seen that the device will make accurate cutting marks on irregular surfaces as well

2

as on a plurality of surfaces which are to be intersected by the installation.

An object of these improvements is to provide a simple yet efficient instrument for marking cutting lines for the installation of a cylindrical unit.

Another object is to provide a longitudinally moveable and rotatable marking device for movement longitudinally of and rotationally about centers corresponding to the center line of a unit after installation.

Another object is to provide a pipe with a longitudinally moveable and rotatably mounted scribe, and aligned supports for the pipe.

Another object is to provide an improved method of marking portions of a structure for cutting.

These and other objects of invention will be manifest from a consideration of the following description, claims and drawings in which:

20 Fig. 1 is a slightly distorted assembly view of my marking instrument in conjunction with a cut-out portion of a structure previously cut along the markings made.

Fig. 2 is a detail assembly of the pipe, a pipe support and scribe.

Fig. 3 is a detail view of a target plate and centerline wire used in the erection of the improved device.

Referring to the drawing, Fig. 1 shows a surface such as a ship's deck 10 having a cut-out portion 11 to receive a shaft or cylinder (not shown). Deck supporting plates 12, 13 and 14 with concave ends 15, 16 and 17 provide supports for the installation. Both the deck and deck supporting plates present a structure resulting from cutting along the marks produced by the improved device. The cutting may be exactly to size and hence the collars previously used are dispensed with.

My improved device and its operation will be understood from its method of erection and the following description:

A centerline wire 20 is conveniently erected, drawn taut, and secured so as to be along the centerline of the shaft or cylinder when it is in installed position. Two or more perforated target plates 21 are slotted as at 22 to permit them to be centered by the wire 20. This centering may be done by the use of braces 23 and clamp 24 after which the legs may be tack welded as at 25 and

50 26. The present improvements contemplate various forms of supports, the illustrated embodiment being preferred for long and relatively narrow marking requirements. When the supports are erected the wire 20 may be removed and a length of $1\frac{1}{4}$ " pipe 27 inserted as shown in Fig.

1. A T connection 28 engages the pipe by a sliding fit to permit both longitudinal and rotary motion relative to the pipe. The T connection 28 constitutes a scribe base portion and is joined by a turned in pipe 29 having a nut 29a welded inside to receive an adjustable screw threaded marker 30. A lock nut 31 will securely lock the marker 30 in adjusted position.

An alternate type hooked scribe 32, Fig. 1, having a hook portion 33 parallel to the centerline of the pipe 27 will mark surfaces forming an obtuse angle with the plane of the centerline as shown in Fig. 1. It will be understood that the pipe may carry one or a plurality of scribes and is removable from the legs or braces 23. In both the straight end marker 30 and the hooked marker 32 the marking point is spaced from the centerline a distance equal to the radius of the shaft or cylinder to be installed. When the straight end marker 30 is moved along the pipe 27 it will scribe a line or mark along which the wall of an intersecting cylinder will cut the deck or surface.

In Fig. 1 three supports 40, 41 and 42 are shown. To mark the portion between supports 40 and 41, all that is necessary is to remove the pipe 27 and transfer the straight end scribe so that it is moveable between these two supports. At the point the cylinder first will intersect the deck a point contact is made which gradually widens out as the marker moves longitudinally and is caused to revolve by the deck or floor.

The pipe 27 will be on any convenient length but I have found that lengths of 12 foot 1 1/4 inch pipe is sufficient for most installations aboard ship.

The hooked scribe 32 likewise moves longitudinally and rotatably if necessary to describe cutting arcs on supporting plates 12, 13 and 14.

Having described my invention in a preferred embodiment, I desire to be limited only by the scope of the appended claims.

This invention may be made or used by or for the Government of the United States for governmental purposes without the payment to me of any royalties thereon or therefor.

What I claim is:

1. The method of setting up a supporting tubular rail for the longitudinally slidable pivot of a scribe of a layout tool comprising setting up a taut wire at the longitudinal center line of a cylindrical object which is to be installed partly through an obstructing surface, securing a plurality of legs to the obstructing surface at an angle normal to the taut wire, securing an apertured slotted rail supporting plate to each leg by sliding the slot in the plate about the taut wire to place the plate with the center of the aperture coinciding with the taut wire and affixing the plate to a leg, then removing the taut wire and positioning the rail through the series of apertures with a scribe pivot between each successive pair of plates.

2. A layout tool comprising a plurality of V legs arranged to be secured to an obstructing surface through which a cylindrical object is to be installed, an apertured plate arranged to be secured at the apex of each pair of V legs with the apertures of each plate axially aligned at the centerline of the cylindrical object in installed position, a tubular rail extending through such aligned apertures and supported by said plates, and a scribe slidably and pivotally supported on said tubular rail between each pair of supporting plates.
